UNITED STATES PATENT OFFICE.

MAYER AXELMAN AND HARRY W. AXELMAN, OF CHICAGO, ILLINOIS.

REINFORCED SUITCASE.

Application filed May 31, 1921, Serial No. 474,048. Renewed November 9, 1925.

To all whom it may concern:

Be it known that we, MAYER AXELMAN and HARRY W. AXELMAN, citizens of the United States, and residents of the city of Chicago, in the county of Cook and State of Illinois, have invented certain new and useful Improvements in a Reenforced Suitcase; and we do hereby declare that the following is a full, clear, and exact description of the same, reference being had to the accompanying drawings, and to the numerals of reference marked thereon, which form a part of this specification.

This invention relates to suit or traveling cases of that type in which two complementary box-like sections are hinged together. In traveling, these cases are roughly handled by express men and others. They are thrown on the cars and on vehicles, frequently upon their ends or corners, with the result that they soon become damaged and broken, greatly decreasing the life thereof.

It is therefore an object of this invention to reenforce a suit case in such a way that it will endure the severe strains and usage to which it is put.

It is a further object of this invention to both transversely and longitudinally brace the case against stresses on any part thereof. With these and other objects in view, which will become more apparent in the following description and disclosure in the drawings, our invention comprises the novel features of construction and combinations hereinafter described and more specifically pointed out in the appended claims.

In the accompanying drawings, which illustrate a preferred embodiment of my invention, and in which similar reference numerals refer to similar features in the different views:

Figure 1 is a perspective side view of a suit case embodying my invention.

Figure 2 is a perspective view of the suit case in open position with the lining removed.

Figure 3 is an end view of the suit case.

Figure 4 is a section on the line 4—4 of Figure 1.

Figure 5 is a section on the line 5—5 of Figure 4.

As shown on the drawings:

For the purpose of illustrating this invention, we have shown a suit case comprising the complementary box-like sections 1

hinged together by the integral piece of leather that constitutes the body of the case. Each box-like section is vertically or transversely braced by means of resilient spring strips 2 secured by rivets 3 or the like 60 to the inwardly extending opening frame 4 at the upper end. These spring strips follow the inner contour of the box-like sections to the bottom hinge portion where they are freely movable. A transverse plate member 5 or the like may extend transversely over the hinge portion for slidably receiving the free ends of the spring strips 2 thereunder. For this purpose the plate 5 may be provided with upwardly bent or 70 stamped sections 6 to provide grooves to receive the free ends of the strips 2 thereunder. Any number of spring bracing strips may be used; in the present instance three strips are used for bracing each box- 75 like section.

In order to brace the case longitudinally to protect the same against shocks arising from throwing the case upon its end, or from other causes, each box-like section is 80 provided with a spring strip 7 secured substantially midway of its height and fastened to the opening frame member 4 by means of rivets 8 or the like. The resilient braces 2 pass under the resilient braces 7 in which 85 grooves are formed by bending sections equal to the width of the braces 2 inwardly so that said braces 2 can pass thereunder.

The vertical braces 2 and the longitudinal braces 7 being secured to the frame member 4, form resilient supports or frame work for the leather covering of the case. The vertical braces may be sheathed by sewing the lining to the leather covering along each margin of said braces, or spiral pieces may 95 be used for sheathing said braces.

It is characteristic of this invention that the resilient bracings form resilient supports or resilient skeleton frames for the leather covering and absorb the shocks or thrusts 100 arising from any rough handling of the suit case, and prevent sagging of the same at any place. It should also be noted that the braces 7 of the resilient skeleton frame act as a truss for the ends of the case so that the same cannot cave inwardly when thrown upon its ends.

We are aware that numerous details of construction may be varied through a wide range without departing from the principles 110

of this invention, and we therefore do not purpose limiting the patent granted otherwise than necessitated by the prior art.

We claim as our invention:

6. 1. In a suit case having a pair of hinged box-like sections and an opening frame secured to said sections, transverse resilient braces conforming to the inner contour of said sections fixedly secured to said frame at their 10 upper end, a grooved plate for slidably anchoring the lower ends of said braces upon the bottom of said case, and horizontal resilient braces having their ends secured to said frame with their body portions con-
15 forming to the contour of said box-like sections to truss the ends of said case.
2. In a suit case having a pair of hinged box-like sections and an opening frame secured to said sections, transverse resilient

braces conforming to the inner contour of 20 said sections fixedly secured to said frame at their upper end, a plate in the bottom of said case having raised portions to form grooves for slidably anchoring the lower ends of said braces, and horizontal resilient 25 braces having their ends secured to said frame with their body portions conforming to the contour of said box-like sections to truss the ends of the case, said transverse braces passing under said horizontal braces, 30 and grooves formed in said horizontal braces to hold said transverse braces against displacement.

In testimony whereof, we have hereunto subscribed our names.

MAYER AXELMAN.
HARRY W. AXELMAN.
